UNITED STATES PATENT OFFICE.

JOSEPH D. PALDI, OF BROCKWAY, MICHIGAN.

FENCE-POST.

SPECIFICATION forming part of Letters Patent No. 744,790, dated November 24, 1903.

Application filed August 26, 1902. Serial No. 121,027. (No model.)

To all whom it may concern:

Be it known that I, JOSEPH D. PALDI, a citizen of the United States, residing at Brockway, in the county of St. Clair and State of Michigan, have invented certain new and useful Improvements in Fence-Posts, of which the following is a specification, reference being had therein to the accompanying drawings.

10 The invention relates to improvements in a fence-post; and it is the object of the invention to obtain a construction which may be cheaply manufactured, which is durable and strong, and one which may be quickly placed 15 in position in the fence.

The invention consists in the peculiar construction, arrangement, and combination of parts with particular reference to the construction of the base, the means for supporting and securing the post proper thereon, the means for attaching the guys to the base, and other details of construction more specifically set forth in the claims.

In the drawings, Figure 1 is a perspective view of the fence, showing three posts of different construction all embodying features of my invention. Fig. 2 is an elevation of one construction of the post. Fig. 3 is a similar view of another construction of the post. Fig. 30 4 is a horizontal section through the base of the post, illustrating the means for attaching the guys. Fig. 5 is a horizontal section through the base of the post, showing the guy-fastening means applied in a slightly-different manner. Fig. 6 is a vertical section thereof. Fig. 7 is a perspective view of a modification of the base together with the means for attaching the guys. Fig. 8 is a perspective view of a securing device for the upper 40 section of the post with the base. Fig. 9 is an elevation showing means of attaching the cap to the post. Fig. 10 illustrates a bent wire previous to being twisted to form the guys. Fig. 11 shows the upper end of the completed 45 guy.

Generally described, my improved fence-post comprises a base-section formed of a cementitious substance, such as vitrified clay, tile, or artificial stone. This base A may be 50 of any suitable shape. As shown in Fig. 2, it comprises a portion a, having a flat top b and provided with an overhanging flange

c. It is also provided near the bottom with a laterally-extending flange or portion d. The object of this lower flange is to prevent 55 the post from heaving, due to the action of the frost, the flange being designed to be placed below the frost-line. The upper flange c is for the purpose of anchoring the guy-clamps, which will be hereinafter described. 60

B is a cap seated upon the top of the base A and having downwardly-extending flanges e e, which hook over the edges of flange c. This cap may be of any desired form, but as shown in the drawings it comprises a flat 65 bar of metal bent to form the hooks e. Centrally of the bar a recess f is formed, adapted to receive the lower end of the upper section C of the post. This upper section is formed in various ways, according to the peculiar 70 kind of post which is desired, the same being preferably formed of resilient material for a purpose to be hereinafter set forth. Thus for the end post I preferably employ angle-bars, while for the intermediate post flat or 75 square bars are used. These intermediate posts are also preferably of two forms. One employed is a flat bar having a greater width than thickness, the other uses a small square bar. These three modifications are all shown 80 in the fence illustrated in Fig. 1 and may respectively be described by the reference-letters D, E, and F.

At the upper end of the section C of the post is arranged a cap G. This is preferably 85 made of cast metal and may be secured to the section C by providing the latter with an upwardly-extending tongue g, engaging a recess h of the cap. Upon opposite sides of this cap guys H are secured, which extend 90 downward to the base A and are secured thereto by the following construction.

I is a band or strap preferably formed of a plurality of sections, each terminating in outwardly-extending ears i. These sections when 95 placed together will completely surround the base A and in the construction shown in Fig. 2 will be immediately below the flange c. The ear I will extend outwardly beyond the flange c and adjacent to each other, and these 100 ears are apertured for the passage of the clamping-bolt J. The bolts J perform the double function of clamping the strap I upon the post and also forming an anchor for the

guys H. These guys may be formed of rods or wires, the construction varying with the peculiar character of post. Thus for the post D and E metallic rods are used which are provided at their lower ends with eyes j, through which the bolts J pass, said eyes being placed intermediate the ears i on the strap I. At their upper ends the guys are each provided with a threaded portion, which passes through m, apertued in the cap G and has engaged therewith a clamping-nut K.

With the construction just described it will be understood that the section C of the post is firmly secured to the base A and cap G by means of the guys H, which at their lower ends are secured by the bolts J to the straps I and at their upper ends by the nuts K to the cap G. The section C is also held from lateral displacement by reason of a metallic cap B on said base, having the flanges e e, which hook over the edges of the base. Obviously the flanges e may be four in number, as clearly illustrated in the end posts of Fig. 1 of the drawings.

In the construction of the post F it rests upon a washer F' on the top of the base. The guys are preferably formed of a plurality of strands twisted together, as at H'. The three strands of this guy are preferably each formed of a single piece of wire bent into a loop, with the ends of the wire overlapping at a point intermediate of the ends of the guy. The loop thus formed and shown in Fig. 10 is then twisted to produce the guy illustrated in Fig. 11, said guy having loops or eyes k formed at each end. The loop k at the lower end is engaged with the clamp-bolt J and at the upper end of loop k engages with the hook L, which has a threaded end passing through an apertured cap and engaging with the nut K. With this construction of guy the strands of the fence may be attached thereto by inserting securing-loops M, of wire, between the twists of the guy adjacent to each of the strands and by then twisting said loop end around said strands. The result will be that the strands will be thus securely fastened to the guys. To further strengthen the post, the guys H' are preferably bound to the section C of the post by means of loops N, embracing both the guys and said section, as shown in Fig. 1. Two of said loops are shown, the lower one, N', being slightly modified by twisting the wires of the loop intermediate of the guy to the central section C. In order to take up the expansion and contraction of the guys, due to variations in temperature, I preferably bend the post F slightly and then tighten up the guys to hold it bent. The guys attached to the post on the side toward which it bends being tightened and held under tension while the guys extending in the direction from which the post is bent serving to prevent any further bending of the post, the tension will thus tend to keep the guys tight at all times.

In place of the construction of base illus-

trated in Fig. 2 I may employ the modified construction shown in Fig. 7. The latter is especially adapted for a cheap construction of post, as the base thus modified may be formed in a brick or tile machine. As shown, the base A' is formed without the flange c, and to then secure the clamp in position a recess p is formed in the base while still in a semiplastic condition. This may be accomplished by a suitable tool for pinching it or in any other desired way. The recess p thus formed is adapted to receive the straps I', which are then clamped in position in the same manner described in connection with the construction shown in Fig. 2.

What I claim as my invention is—

1. A fence-post comprising a base having an outwardly-extended flange at its upper end, a metallic cap for the base comprising a flat surface and elongated projections at each of its sides struck down to form flanges for overlapping the flanges of the base, an upper post-section seated upon the cap, and guys for securing the upper section to the base. 85
2. A fence-post comprising a base, a strap surrounding said base and having adjacent outwardly-projecting ears at its ends, a bolt passing through said ears for clamping said strap upon said base, an upper post-section supported upon said base and a guy attached at its upper end to said upper section and secured at its lower end to said clamping-bolt, whereby said guy is detachably secured to the base. 95
3. A fence-post comprising a base, a strap surrounding said base formed of a plurality of sections having their adjacent ends terminating in outwardly-projecting ears and bolts passing through said ears for securing said sections together, an upper post-section seated upon said base and a plurality of guys attached at their upper ends to said upper section and secured at their lower ends to said bolts, whereby a detachable connection for the guys is formed. 105
4. A fence-post comprising a base formed of cementitious material having a shoulder at its upper end, an adjustable strap surrounding said base below said shoulder, a clamping-bolt for securing the ends of said strap together, an upper post-section seated upon said base and a guy for said upper section secured at its lower end to said clamping-bolt, whereby a detachable connection for the guys is formed. 115
5. A fence-post comprising a base formed of cementitious material having a projecting annular flange at its upper end, a detachable strap surrounding said base below said flange and formed in a plurality of sections, clamping-bolts for securing said sections together, an upper post-section seated upon said base and guys for said upper section secured to said clamping-bolts, whereby a detachable connection for the guys is formed. 125
6. A fence-post comprising a base, an upper post F of resilient metal seated thereon, a cap

upon the top of the metal post, guy-rods connecting the cap and the base, the post being slightly bent and maintained in its bent condition by the guy-rods, whereby tension is 5 constantly maintained upon said guy-rods regardless of changes in atmosphere.

7. A fence-post comprising a base having a shoulder at its upper end, an adjustable strap surrounding said base below said shoulder 10 formed of a plurality of sections having their adjacent ends terminating in outwardly-projecting ears and bolts passing through said ears for securing said sections together, an upper post-section seated upon said base, and 15 a plurality of guys for said upper section secured at their lower ends to said bolts, the said bolts forming a detachable securing means for the guys.

8. A fence-post comprising a base having a shoulder at its upper end, an upper post-section seated upon said base, guys for the post-section, and adjustable means engaging under the surface of said shoulder and surrounding the base to which means are 20 secured the guys.

9. A fence-post comprising a base, an upper

post-section seated upon said base, guys for the upper section, and means passing around the base comprising a plurality of sections adjustably secured together to which are secured the guys. 30

10. A fence-post comprising a base, an adjustable strap surrounding said base, a clamping-bolt for securing the ends of said strap together, an upper section seated upon said base, and a guy for said upper section secured at its lower end to said clamping-bolt whereby a detachable connection for the guy is 35 formed.

11. A fence-post comprising a base having a shoulder at its upper end, an upper post-section seated upon said base, guys for the upper post-section, and adjustable means surrounding the base engaging the under surface of said shoulder and to which the guys are 40 secured, said means being detachable.

In testimony whereof I affix my signature in presence of two witnesses.

JOSEPH D. PALDI.
